(57) **CLAIM**

The ornamental design for the bird guard for an insect trap, as shown.

DESCRIPTION

FIG. 1 is an upper-front-left view of a bird guard for an insect trap in accordance with the present invention; FIG. 2 is a front view of the bird guard for an insect trap shown in FIG. 1; FIG. 3 is a back view of the bird guard for an insect trap shown in FIG. 1; FIG. 4 is a top plan view of the bird guard for an insect trap shown in FIG. 1, which due to symmetry is the same as a bottom plan view; and, FIG. 5 is a left side view of the bird guard for an insect trap shown in FIG. 1, which due to symmetry is the same as a right side view.
